(57) **CLAIM**

The ornamental design for a combined ceiling fan motor
housing and light fixture unit, as shown and described.

DESCRIPTION

FIG. 1 is a perspective view thereof;

FIG. 2 is a front elevational view thereof;

FIG. 3 is a right side view thereof;

FIG. 4 is a left side view thereof;

FIG. 5 is a top plan view thereof; and,

FIG. 6 is a bottom plan view thereof.

The broken line showing of environmental structure in
FIGS. 1-6 is for illustrative purposes only and forms no part
of the claimed design.
